VAT FOR ELECTRO-METALLURGY

Jean-Charles Simon-Suisse, Montbonnot, France, assignor, by mesme assignments, to Pechiney, Compagnie de Produits Chimiques et Electrometallurgiques, Lyon, France, a French company

Application March 15, 1955, Serial No. 494,516

Claims priority, application France March 29, 1954

6 Claims. (Cl. 204—243)

The present invention relates to the construction of vats used in the electro-metallurgical industry, and especially to those vats of the kind which are used in the production of aluminium by electrolysis.

Vats of this kind are generally constituted by a metallic casing which is internally lined with a suitable lining known as brassing. In the case of vats which are used in the preparation of aluminium by electrolysis, it is the brassing which forms the cathode or anode, whilst at the same time it receives the bath of alumina and molten aluminium.

In the usual form of construction, the casing of these vats, formed by a bottom and four sides, has the appearance of a box open at its upper part. The bottom and the sides are stiffened by the types of reinforcement usually employed in metal construction work, so as to withstand both static stresses and the deformation which can be produced due to various causes.

Now it has been observed that in spite of the strengthening of the members of the vat, breaking or deformation frequently occurs and this is particularly serious since they sometimes result in the collapse of the bath. In addition, whatever precautions may have been taken, the brassing contained in the vat rapidly deteriorates and it becomes necessary to replace it frequently, and this constitutes an unfortunate and very costly drawback.

The present invention has for its object to overcome these drawbacks and to improve the performance and the life of these vats, both in respect of the metallic casing and its internal lining.

The invention is characterized in that the vat is constituted by a casing of multiple elements which can be subjected to a relative displacement with respect to each other, the elements being mounted with elastic restoring means upon the fixed support of the vat.

The vats formed in this manner and its interior lining have a certain freedom for swelling and deformation; they stand up better and for a longer time to the stresses due to the transformation of the lining during the course of the metallurgical processes. Whilst in the case of rigid vats of previous kinds, accidents frequently occur due to breaking of the brassing, such accidents are avoided with vats having walls with elastic displacements which can follow the deformation of the brassing without causing rupture of this latter.

In producing the vat in accordance with the invention, the usual means of strengthening the vat, intended to render it capable of withstanding the stresses due to the transformation of the brassing, are eliminated. This results in a considerable reduction in weight and a substantial economy. As the dead weight is reduced, the supports may also be appreciably lighter. As they no longer have to withstand deformation, the value of which is difficult if not impossible to estimate, the elements may be exactly calculated as a function of perfectly well-known stresses, without the excess of material which is usually provided as a measure of safety.

2

The attached drawings show by way of example methods of manufacture of casings for vats used in the electrolysis of aluminium, in accordance with the invention.

5 Fig. 1 is a diagrammatic view in perspective of the general arrangement of the vat.

Fig. 2 is a half view in longitudinal cross-section.

Fig. 3 is a half view in transverse cross-section.

10 Fig. 4 shows in cross-section the details of the coupling of the sides of the elements with the base of the vat.

Fig. 5 is a plan view corresponding to Fig. 4.

Fig. 6 is a longitudinal cross-section of an alternative form of embodiment.

Fig. 7 is a transverse cross-section of the alternative form shown in Fig. 6.

Fig. 8 shows a longitudinal cross-section of a further form of embodiment.

Fig. 9 is an explanatory curve in connection with the form of embodiment shown in Fig. 8.

The vat in accordance with the invention, instead of being formed by a casing in one single piece, is made up of elements or members which can have a certain relative movement with respect to each other.

As shown diagrammatically in Fig. 1, the metallic casing 25 is composed of a flat member 1 which forms the base, of longitudinal sides 2 and of transverse sides 3. These members are separate and are placed one on the other without being assembled together in a rigid manner. They are simply connected with means of attachment 30 which leave a sufficient degree of freedom to permit of them sliding with respect to each other. These members 1, 2 or 3, which are separate and simply placed on each other, are carried by means of suitable supports, having preferably elastic movement, of which different forms 35 of construction will be described later. The casing, once formed by the placing in position of the members 1, 2 and 3, is lined internally with suitable brassing. The lining is designated L in Fig. 1 and is shown partially broken away; in the other figure, the lining L is not shown for simplicity.

In order to compensate for the stresses due to the deformation of the brassing, without however preventing the movement of the walls 2 and 3, elastic means, such as springs 4, are applied against the walls, the said springs 40 being supported on the members 5 of the fixed steel framework. The springs 4 are adjustable in such manner that the compression forces which they apply to the sides 2 and 3 of the casing are amply proportioned with respect to the stresses produced by the deformation of the interior brassing.

The details of the construction of the vat in accordance with Fig. 1 are shown in Figs. 2 and 3.

On the foundation 6 consisting of a solid block or low 55 walls of concrete, are mounted the members of the metallic framework which constitute the support for the vat. These members consist of girders 7 spaced-apart and connected to upright members 8. The girders 9 which carry the plate 1 forming the base of the vat are mounted on the girders 7. The girders 9 are rigidly fixed 60 externally to the uprights 10.

On the base 1 is applied the bottom folded-in edge 11 of the sides 2. Each of these sides 2 is carried by a cradle 12 to which are fixed the supporting members 13. The latter are formed by elastic spring blades which are 65 fixed to the cradle 12 at 14 and at their other extremities to the brackets 15 which are rigidly secured to the girders 9. This assembly permits the sides 2 to have a horizontal sliding movement without frictional contact.

In an alternative form, the mobility of the sides 2 may be obtained by mounting the cradles 12 on rollers trav-

elling along the girders 9, or again by means of slide-tracks in sliding contact with these girders.

The cradles 12 are retained and stayed by means of springs 16 attached to the upright member 10. The springs 16 are arranged so as to be adjustable as a function of the stresses of the brasking on the side 2. The transverse sides 3 of the vat are mounted in a similar way to the longitudinal sides 2 (see Fig. 3) with their folded-in edge 25 applied against the base 1 of the vat. The side 3 is carried by the cradles 17 which are themselves supported on spring blades 18 secured to angle-iron members 19 rigidly fixed to the girder 7 (or by rollers or slides). The cradles 17 are stayed, in opposition to the stresses due to the deformation of the brasking, by means of springs 20 which are fixed to the upright members 8, and which are adjustable.

In order to carry out the adjustment of the springs 16 (or 20) and to keep their length within reasonable limits of space, the contact face 21 of the spring is firmly secured to a screw 22 inserted in a threaded sleeve 23 fixed to the support 10 (or 8). The screw 22 is provided with a square section 24 intended to receive the lever or the adjusting key. In order to check the adjustment of the springs 16 and 20, it is an advantage to provide a gauge rigidly fixed on the cradle 17 (or 12), the position of which with respect to a fixed member such as the uprights 8 or 10, enables the length of the spring to be observed and in consequence the load which it carries may be estimated.

As shown on the drawing, the sides 2 and 3, supported by the cradles 12 and 17 capable of longitudinal movement, have their edges 11 and 25 overlaid on the base 1 which is fixed on the girders 9. During working, when the brasking of the vat exerts a lateral thrust, the sides 2 and 3 lend themselves to deformation, whilst at the same time they are retained by the springs 16 and 20.

In order to permit of this sliding movement of the edges 11 and 25 without the latter becoming displaced from the base 1 by a dangerous amount, they are connected to the base 1 in the manner shown in Figs. 4 and 5. The sliding edge, 11 for example, is provided with a series of rivets 26, the shanks 27 of which are engaged in elongated slots 28 formed in the base 1. The head 29 of each rivet engages with a circular plate 32 which is wider than the slot 28. This plate 32 is retained in position by a spacing collar 31 fitted on the shank 27 of the rivet 26.

With this arrangement, the edge 11 slides over the base 1 in accordance with the necessities of the deformation of the brasking, without ever ceasing to be in contact with the base 1 and without however having to be subjected to excessive friction. At the upper part of the vat, metal lips 33 and 34 are fixed to the upper edge of the sides 2 and 3 and rest on the slabs 35 which form the service floor.

In the alternative form of embodiment shown in Figs. 6 and 7, the cradles 12 and 17 are dispensed with. To the sides 2 and 3 of the vat are directly fixed supporting pillars which rest directly on the foundations. To each of the sides 2 is fixed a pillar 36, of which the free lower end 37 can be supported on a portion 38 of the concrete block 6, but without however being fixed in it. The pillars 36 of the two opposite sides 2 are coupled together by a tie-rod 39, the tension of which is adjustable. The tie-rod 39, fixed on the pillar 37 at one side is fixed to the pillar 37 on the other side to the intermediary of a calibrated spring 40. The tension of the spring 40 is regulated by the nut 41 which screws on to the threaded end of the tie-rod 39.

In the form of construction shown, which comprises two contiguous sets of pillars 37, there can be seen the symmetrically-mounted tie-rods of the two pillars, the tie-rod of the second pillar being shown at 39' with a spring on the opposite side to the spring 40. Each of

the transverse sides is provided with a pillar 42, the lower end 43 of which is free. On the pillar 43 is mounted, through the intermediary of the spring 44, adjustable by the nut 45, a tie-rod 46. The other end of the tie-rod 46 is fixed to a member 47 which is attached to the steel framework 7.

The casing thus made up of elastically-sliding sides may be provided with orifices such as the slots 48, for introduction of current-carrying bars, which are formed in the base 1 and, if this is necessary, in the sides 3. The reference number 49 indicates the assembly of rivets and elongated slots which couple the sides 2, 3 with the base 1 or with each other.

Instead of effecting the tensioning arrangements by tie-rods with adjustable springs, the tensile stresses of the tie-rods themselves may be employed, with the condition that these stresses are made to correspond to the zone of plastic deformation of the steel of which these tie-rods are made.

In this case, as is shown in Fig. 8, the tie-rod 39 connecting two pillars 37 is fixed to these pillars in a rigid manner at 50. The dimensions of the tie-rod are chosen so that under the pressure P which it is necessary to apply to the walls of the vat in order to obtain suitable cohesion of the linings, it is subjected to a stress F which corresponds to the point A of the stress-deformation curve for the metal (see Fig. 9), this point A being the elastic limit of the metal employed.

From the moment at which the pressure P is reached, the walls of the vat are displaced outwards and the tie-rod stretches, following the line A—B of plastic deformation, without appreciable increase in the stress F applied to the tie-rod. Nevertheless, the wall may move back so as again to be located on the deformation curve A—B. If, for example, an accidental contraction of the brasking has taken place, the stress on the tie-rods falls away sharply and the metal which has reached the point C in the zone of plastic deformation, follows the path C—D parallel to O—A. When the wall again takes up its position, the metal follows the path D—E and then continues its elongation along the portion E—D.

The displacement of the sides of the vat, retained in this way by tie-rods with controlled elastic limit, is effected under a substantially constant stress by the elasticity itself of the metal of the tie-rods which are of carefully selected steel and the dimensions of which have been calculated to that end. The lining used in the vat is identical with that ordinarily employed in vats of the same kind. An example of such a lining can be found in U. S. Patent No. 2,593,751 to Grolee, issued on April 22, 1952. Such lining forms no part of the invention, which is concerned exclusively with the framework of the vat.

What I claim is:

- 55 1. Apparatus for electro-metallurgy comprising a metallic casing having a carbonaceous lining and comprising five separate elements, namely, a flat bottom, and four sides slidably engaging said bottom, support means comprising means underlying and sustaining said flat bottom, adjustable elastic means mounted on said support means and operatively engaging said sides for permitting movement of said sides relative to said bottom.
- 60 2. Apparatus for electro-metallurgy as in claim 1, and further comprising cradles supporting said sides, and second support means carried by said first support means and connected to said cradles and permitting horizontal movement of said sides.
- 65 3. Apparatus for electro-metallurgy as in claim 2, said second support means comprising flexible blades.
- 70 4. A vat as set forth in claim 1, wherein the sides are provided with inturned horizontal portions, which portions slide on the flat bottom.
- 75 5. A vat as set forth in claim 4, wherein the flat bottom is provided with elongated slots and the inturned

portions are provided with rivets having the shanks thereof slidably mounted in said slots.

6. A vat as set forth in claim 1, wherein the adjustable elastic means comprise a steel tie rod having a controlled elastic deformation and provide an elastic tension between each pair of sides of the casing and at right angles to said sides.
